US0D1076083S

(12) **United States Design Patent** (10) Patent No.: **US D1,076,083 S**
(45) Date of Patent: ** May 20, 2025

(54) **SURGICAL SNARE**

(71) Applicant: **OLYMPUS CORPORATION**,
Hachioji (JP)

(72) Inventors: **Yuta Muyari**, Hino (JP); **Akane Yasukawa**, Hachioji (JP); **Mitsunori Kubo**, Hachioji (JP); **Takayuki Kikuchi**, Inagi (JP); **Aya Mori**, Hachioji (JP); **Miho Naka**, Hachioji (JP); **Yoshino Nagasuka**, Hachioji (JP)

(73) Assignee: **OLYMPUS CORPORATION**,
Hachioji (JP)

(**) Term: **15 Years**

(21) Appl. No.: **29/754,566**

(22) Filed: **Oct. 13, 2020**

Related U.S. Application Data

(62) Division of application No. 29/640,036, filed on Mar. 12, 2018, now Pat. No. Des. 903,116.

(57) **CLAIM**

The ornamental design for a surgical snare as shown and described.

DESCRIPTION

FIG. 1 is a front perspective view of a surgical snare showing our new design;

FIG. 2 is a front view thereof, a rear view being a mirror image of FIG. 2;

FIG. 3 is a top view thereof, a bottom view being a mirror image of FIG. 3;

FIG. 4 is a right side view thereof; and,

FIG. 5 is a left side view thereof.

The broken lines shown in the figures illustrate portions of the surgical snare that form no part of the claimed design.
